US0D1050163S

(12) **United States Design Patent** (10) **Patent No.:** **US D1,050,163 S**
(45) **Date of Patent:** **** Nov. 5, 2024**

(54) **DISPLAY SCREEN OR PORTION THEREOF HAVING A GRAPHICAL USER INTERFACE**

(71) Applicant: **Flo Free LLC**, Red Bank, NJ (US)

(72) Inventor: **David James Mozeika**, Red Bank, NJ (US)

(73) Assignee: **Flo Free LLC**, Red Bank, NJ (US)

(**) Term: **15 Years**

(21) Appl. No.: **29/910,523**

(22) Filed: **Aug. 21, 2023**

Related U.S. Application Data

(62) Division of application No. 29/835,321, filed on Apr. 18, 2022, now Pat. No. Des. 996,457, which is a division of application No. 29/687,264, filed on Apr. 11, 2019, now Pat. No. Des. 949,877.

CLAIM

The ornamental design for a display screen or portion thereof having a graphical user interface, as shown and described.

DESCRIPTION

A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

The FIGURE is a front view of a display screen or portion thereof having a graphical user interface.

The dashed broken lines depict portions of the display screen or portion thereof having a graphical user interface that form no part of the claimed design. The dot-dashed lines depict portions of the display screen or portion thereof and boundaries of the claimed design that form no part of the claimed design.
